(57) **CLAIM**

The ornamental design for a bicycle headlight, as shown and described.

DESCRIPTION

FIG. 1 is a perspective view of a bicycle headlight showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the bicycle headlight on a cradle shown in use environment; and,

FIG. 10 is an enlarged view of the bicycle headlight shown within the area designated as 10 in FIG. 1.

The broken lines in the drawings are for the purpose of illustrating portions of the bicycle headlight that form no part of the claimed design. The other broken lines showing a cradle in FIG. 9 are for the purpose of illustrating environment and form no part of the claimed design.
